(57) **CLAIM**

The ornamental design for a star shaped driver, as shown and described.

DESCRIPTION

FIG. 1 is a front upper perspective view of a star shaped driver.

FIG. 2 is a front lower perspective view of the star shaped driver of FIG. 1.

FIG. 3 is a front view of the star shaped driver of FIG. 1, of which the back view is a mirror image thereof.

FIG. 4 is a left side view of the star shaped driver of FIG. 1, of which the right view is a mirror image thereof.

FIG. 5 is an enlarged top view of the star shaped driver of FIG. 1; and,

FIG. 6 is an enlarged bottom view of the star shaped driver of FIG. 1.

The broken lines immediately adjacent the shaded areas represent a slope change while all other broken lines are directed to environment and are for illustrative purposes only. The broken lines form no part of the claimed design.
